US00D791629S

(12) **United States Design Patent** (10) **Patent No.:** **US D791,629 S**
(45) **Date of Patent:** **** Jul. 11, 2017**

(54) **FLUID LEVEL INDICATOR**

(71) Applicants: **Jon Haworth**, Hendersonville, TN (US); **Houston Hatchett**, Franklin, TN (US); **Keith Mawdsley**, Hendersonville, TN (US)

(72) Inventors: **Jon Haworth**, Hendersonville, TN (US); **Houston Hatchett**, Franklin, TN (US); **Keith Mawdsley**, Hendersonville, TN (US)

(73) Assignee: **Des-Case Corporation**, Goodlettsville, TN (US)

(**) Term: **15 Years**

(21) Appl. No.: **29/542,778**

(22) Filed: **Oct. 16, 2015**

(51) LOC (10) Cl. **10-04**

(52) U.S. Cl.

USPC **D10/101**; D10/102; D16/134; D23/249

(58) **Field of Classification Search**

USPC D10/56, 101, 102; D16/134, 135; D23/249

CPC G01F 23/02; G01N 1/10

(57) **CLAIM**

The ornamental design for a fluid level indicator, as shown and described.

DESCRIPTION

FIG. 1 is a side perspective view of an embodiment of the fluid level indicator of Applicants' invention.

FIG. 2 is a side view of an embodiment of the fluid level indicator of Applicants' invention.

FIG. 3 is a bottom perspective view of an embodiment of the fluid level indicator of Applicants' invention.

FIG. 4 is a top view of an embodiment of the fluid level indicator of Applicants' invention.

FIG. 5 is a side view of an embodiment of the fluid level indicator of Applicants' invention.

FIG. 6 is a bottom view of an embodiment of the fluid level indicator of Applicants' invention.

FIG. 7 is a side view of an embodiment of the fluid level indicator of Applicants' invention.

FIG. 8 is a side view of an embodiment of the fluid level indicator of Applicants' invention; and,

FIG. 9 is a cut-a-way side view of a portion of an embodiment of the fluid level indicator of Applicants' invention. The broken lines depict portions of the fluid level indicator that form no part of the claimed design.
